UNITED STATES PATENT OFFICE.

NICHOLAS SIMMER, OF GRAND FORKS, NORTH DAKOTA.

DESIGN FOR A STANDARD FOR HAT-HOLDERS.

SPECIFICATION forming part of Design No. 36,333, dated May 19, 1903.

Application filed September 30, 1902. Serial No. 125,442. Term of patent 14 years.

To all whom it may concern:

Be it known that I, NICHOLAS SIMMER, a citizen of the United States, residing at Grand Forks, in the county of Grand Forks and State of North Dakota, have invented and produced a new, ornamental, and original Design for Standards for Hat-Holders, of which the following is a specification, reference being had to the accompanying drawings, forming a part thereof.

Figure 1 is a side elevation of my design, a standard for hat-holders. Fig. 2 is a simi-

lar view from another point of view. Fig. 3 is a top plan view.

What I claim as my invention, and desire to secure by Letters Patent, is—

The ornamental design for a standard for hat-holders, substantially as shown.

In testimony whereof I have affixed my signature in the presence of two witnesses.

NIC. SIMMER.
